UNITED STATES PATENT OFFICE.

CHARLES A. MOORE, OF ST. PAUL, MINNESOTA, ASSIGNOR TO MOORE PATENT CAR CO.,
A CORPORATION OF MINNESOTA.

REFRIGERATOR-CAR.

1,113,135.

Specification of Letters Patent.

Patented Oct. 6, 1914.

Application filed April 17, 1907. Serial No. 368,791.

To all whom it may concern:

Be it known that I, CHARLES A. MOORE, a citizen of the United States, residing at St. Paul, in the county of Ramsey and State of Minnesota, have invented a new and useful Improvement in Refrigerator-Cars, of which the following is a specification.

The primary object of this invention is the production of a refrigerator car of improved construction which is adapted to prevent the racing of ice on the floor of the bunker. A further object is the production of a strong and durable ice bunker in the top of a car with its ends remote from the ends of the car, said bunker being provided with an improved floor, which performs the function of preventing the ice moving too freely therein, and at the same time is adapted to drain water efficiently from the ice. Depending in part upon these requirements my invention comprises the features of construction and combinations of parts herein-after described and claimed.

In the accompanying drawings, forming part of this specification, Figure 1 is a longitudinal vertical sectional view of a portion of a refrigerator car illustrating my invention; Fig. 2 is a plan view partly in section on the line Z—Z of Fig. 1; Fig. 3 is a cross section of Fig. 1 taken on the line Y—Y; Fig. 4 is another cross sectional view of Fig. 1 taken on the line X—X; Fig. 5 is a detail of a horizontal sectional view of a portion of the car, looking down upon its floor immediately above the heating apparatus; Fig. 6 is a detail perspective view of the I beams used in the ice bunker showing the method of joining the same; Fig. 7 is a detail sectional view of the side of the refrigerator car illustrating the manner of fastening the I beams in the ice bunker; Fig. 8 is a detail sectional view of a portion of the ice bunker showing the floor construction thereof and one of the drains leading therefrom; Fig. 9 is a plan view of that portion of the ice bunker shown in Fig. 8; Fig. 10 is a detail sectional view taken on the line Z'—Z' of Fig. 9, and Fig. 11 is a detail sectional view in perspective of the lower portion of one of the ends of the car showing the air-conducting passageway and one of the ports leading from the passageway into the car.

The car body proper, that is, its side walls A, roof B, ends C, and flooring D is made in any desired form and I do not limit

the application of my particular improvements to the special and general construction shown in the drawings. The walls, flooring, and roof of the car are preferably made double, treble, or quadruple with any desired number of dead air spaces E between the separate portions of the wall which air spaces may, if desired, be filled with any suitable material which will serve to insulate the interior of the car. The inner space F, however, is for live air and not filled with material of any kind and is adapted to conduct the hot and cold air issuing from the heater and ice bunker G into the car. The inner space F is formed by the inner walls of the car and the lining 2, the latter being placed a short distance from said inner walls.

The ice bunker G consists of a tray I which is supported on the sides substantially midway between the ends of the car by transverse and longitudinal I beams 4 and 5 and channel beams 5', said beams being connected at their intersections by angle plates 6 (see Fig. 6) and rivets 7 passing through said angle plates and I beams. The ends of the I beams are fastened to the sides of the car by means of bolts 8 passing through a portion of the frame of the walls and the longitudinal channel beams. The tray of the ice bunker is made by resting layers of floor planks 9 across the lower flanges of the beams and placing thereon longitudinal strips 10 upon which transverse angle slats 11 are placed with their apexes directed upward. The blank bottom of the tray may be rendered watertight for drainage purposes in any suitable manner. The angle slats support the ice in the bunker and the water from the ice drips between said slats upon the floor of the tray from which it passes to the exterior of the car through pipes 12 extending downwardly through the side walls. The transverse beams 4 extend upward for a part of their height into the ice bunker forming stops to prevent the skidding of the ice in the bunker. The sharp upturned backs of the angle slats 11 lying transversely of the bunker engage the ice and tend to prevent longitudinal movement. The floor of the bunker as illustrated is substantially horizontal but may be sloped toward the sides of the car if desired to facilitate drainage. The frame of the car adjoining the ice bunker is reinforced by

the braces 13. The ends of the ice bunker are of open work construction and provided with downwardly and inwardly inclined horizontal slats 14, which are spaced apart, 5 so that air may pass through the ends of the bunker freely. Cold air being heavier than warm air passes from the bunker after being cooled by ice therein through the openings between the slats 14 down into the lading chamber in the car, and warm air in the 10 top of the car passes through the openings 15 in the ends and sides of the car, and to the ice bunker through the flues F.

It is understood that the ends of the 15 bunker are of construction similar to each other, the drawings illustrating but one end.

The openings 15 are provided with horizontal slats 17, spaced apart, and the openings 16 with a cover of wire netting 18 (Fig. 20 11). In the roof of the car are hatchways 25 entering the ice bunker and having inner walls 26 contracting toward their lower ends so that stoppers 27 can be inserted in 25 said openings to seal the passageways through which ice is placed in the bunker. Doors 28 are adapted to close the openings 25 in the usual manner. Chains 29 having their ends connected with the frame of the 30 roof and the stoppers 27 are adapted to prevent the stoppers being carried away when they are removed.

The heater H consists of a chamber 30 having suitable heat insulated walls 31 which are suspended below the floor and 35 substantially midway between the ends of the car and provided with a doorway 32 (Fig. 4) through which access can be had to the interior of said chamber. In this heating chamber is placed a stove 33 which carries a supply of oil or any suitable fuel. Air is admitted to this heater by valved 40 passageways 34 leading through the walls of the heater and conducted therefrom by the space F which opens into each end near 45 the top of the heating chamber as shown. A suitable vent pipe 35 leads from the heater and is divided into branches 36 through the side walls and roof of the car for the escape of gases or smoke.

50 The heater may be of any suitable form and may be operated by oil, coal, or other suitable fuel. It is obvious that the heat may be generated in the heating chamber by a coil supplied with steam from a locomotive without departing from the principles 55 which I have applied.

In operation, when it is desired to cool the atmosphere in the car, ice is placed in the 60 bunker through the hatchways in the roof which are afterward sealed. The cold air from the bunker passes down into the car through the openings between the slats 14 and the warm air in the car returns into the bunker through the openings 15 in the 65 ends and sides of the car. When the car is

used for cooling purposes, the valved inlets 34 are closed. When it is desired to heat the car, the valves 37 are opened and the stove 33 operated. Air then freely circulates around the heater and passes up into 70 the car through the conducting passageway and ports 15 and 16. It also enters the car through the ice bunker from above. In this manner warm or cold air freely circulates through the car when the heater or refrigerator is in operation. Outside air also enters the heating chamber through the 75 openings 42.

A ventilator 38 in the roof of the car and entering the ice bunker is provided. Normally this ventilator is closed by a valve 39 pivoted upon a support 40 and carrying a counter-weight 41. To open this ventilator, the valve is swung completely around its pivot support 40 with its counterweight on the opposite side of said support to that illustrated in Fig. 1. When the ventilator 38 and the valves 37 are opened and the car is at rest or in motion fresh air is admitted into the car and freely circulated there-through. By properly ventilating the car, fruit and other commodities in transit are kept fresh and prevented from deteriorating.

In accordance with the patent statutes, I 95 have described the principle of operation of my invention, together with the apparatus which I now consider to represent the best embodiment thereof, but I desire to have it understood that the apparatus shown is 100 only illustrative and that the invention can be carried out by other means and applied to uses other than those above set forth within the scope of the claims.

Having described my invention, what I 105 claim as new and desire to protect by Letters Patent, is:—

1. In a refrigerating car having a provision chamber, an ice bunker in said provision chamber consisting of flanged metal 110 beams attached to the upper part of the side walls of said car, longitudinally thereof, other flanged metal beams lying transversely of the car and framed into said longitudinal beams, a drainage tray supported on the 115 flanges of said beams and having a drainage connection with the exterior of the car and angle bar slats supported above said drainage tray, having their apexes projecting upward to support and engage the ice 120 in the bunker.

2. In a refrigerator car having a roof of uniform construction throughout its length, an ice bunker near the roof of said car and below it, transverse metal beams supporting and carried by the walls of said car, 125 said beams extending through the floor of said bunker to divide the same into ice retaining compartments, and transverse metal slats carried in said bunker, and having 130

upwardly projecting sharp edges adapted to engage and prevent the longitudinal racing of ice in the bunker when said car is in motion.

- 5 3. In a refrigerator car having a body of substantially uniform cross-section throughout its length, an ice bunker within said car body independent of the roof of said car and isolated from its ends, transverse metal beams carried by the side walls of said car and supporting said bunker, and projecting through the floor thereof, and transverse metal slats having sharp top edges supported by the floor of said bunker, said slats and beams forming an anti-skidding device adapted to prevent the longitudinal movement of ice within the bunker.
- 10 4. A refrigerator car having a body of substantially uniform cross-section throughout its entire length, an overhead ice bunker
- 15
- 20

within said body below the roof of the car isolated from its ends and having a floor, the ends of said bunker having passages into the top of the provision chamber to permit circulation of air through said bunker and provision chamber, and a plurality of transverse beams carried by the side walls of the car and projecting above and supporting the floor of said bunker independent of the roof of the car, whereby ice resting upon said floor is prevented by said beams from racing due to longitudinal movement of the car.

In testimony whereof, I have signed my name to this specification, in the presence of two subscribing witnesses.

CHARLES A. MOORE.
